UNITED STATES PATENT OFFICE.

PETER HENRY HIXON, OF CHICAGO, ILLINOIS.

SHOE-POLISHING STAND.

No. 808,986.

Specification of Letters Patent.

Patented Jan. 2, 1906.

Application filed January 6, 1905. Serial No. 239,934.

To all whom it may concern:

Be it known that I, PETER HENRY HIXON, a citizen of the United States, residing at Chicago, in the county of Cook and State of Illinois, have invented a new and useful 5 Shoe-Polishing Stand, of which the following is a specification.

This invention relates to shoe-polishing stands, and has for its object to improve the 10 construction and increase the convenience and efficiency of devices of this character.

With these and other objects in view, which will appear as the nature of the invention is better understood, the same consists 15 in certain novel features of construction, as hereinafter fully described and claimed.

In the accompanying drawings, forming a part of this specification, and in which corresponding parts are denoted by like designating characters, is illustrated the preferred 20 form of embodiment of the invention capable of carrying the same into practical operation.

In the drawings thus employed, Figure 1 is a perspective view of an approved form of 25 the device. Fig. 2 is a transverse section of the same. Fig. 3 is a detail view of the folding step.

The improved device comprises a hollow base provided with supporting-legs and a receptacle and adapted for supporting a chair 30 or other form of seat and having spaced foot-rests detachably connected and adapted for storage in the receptacle when not in use.

The device may be of any desired size or 35 height or arranged to support any number of chairs and provided with corresponding foot-rests, and for the purpose of illustration a device large enough to support two chairs is shown; but it will be understood that I do not 40 limit myself in any manner to the size of the device or to the number of the chairs and foot-rests which it is capable of supporting.

The base member, represented as a whole at 10, is supported upon suitable legs 11 and 45 provided with receptacles, two of which are indicated at 12 in the illustration. Between the receptacles a guide 13 is formed for a drawer 14, which may be employed for any desired purpose, such as a money-drawer, a 50 storage for the polishing material and implements, or the like. The rear portion 15 of the top of the base is continuous and forms a closure to the rear portions of the receptacles and also to the drawer 14 and is provided 55 with an upwardly-extending rim 16, the cover portion 15 being adapted to support

the chairs and the rim to prevent them from displacement therefrom. The forward portions of the base are provided with hinged covers 17, forming closures to the receptacles 60 and affording ready access thereto. The cover members 17 are provided with hasps 18 for engaging staples 19 on the fronts of the receptacles to provide for locking the closures, as by padlocks 20, one of which is 65 shown in position. Spaced notches forming seats 22 are formed in the front wall of the receptacles 12, the cover members 17 closing the upper open ends of these notches or 70 seats.

Within the receptacles 12 spaced steps 23 are formed in a transverse bar to receive the lower ends of the foot-supporting members, which consist of foot-rests 25, having stems inserted through the seats 22 and detachably 75 fitted at their lower ends in the steps 23, as shown in Fig. 2. When not in use, the stems 24 may be detached from the steps 23 and moved into the receptacle, as at the right in Fig. 1, or detached entirely and stored in the 80 receptacle, as may be required. When detached and thrust into the receptacle, as at the right in Fig. 1, the foot-rests occupy less room and are not in the way of passers-by or of the person in mounting to or descending 85 from the chairs on the platform.

The legs 11 will be preferably long enough to enable the operator to sit or stand while at work, and a step will be provided to enable the patron to readily mount the platform, 90 and this step consists of a plate 26, movably mounted beneath the base for projecting therefrom when required for use and for sliding beneath the same when not required. The plate is disposed for movement between 95 ways or guides 27 and limited in its movement by a slot 28 and bolt 29 and is also provided with a standard 30, hinged at 31 to the plate and connected thereto by folding braces 32. The bars 24 are provided with short chains 33, adapted to be coupled to the staples 19 by the lock members 20, as shown, to prevent the surreptitious removal of the 100 foot-supporting members.

A flexible connection consisting of the 105 chains 33, by which each foot-rest is permanently connected with the front wall of the base, is adapted when the foot-rest is arranged within the receptacle to be extended through the notch or seat in which the stem 110 of the foot-rest is adapted to be fitted when the latter is in use, the staple 19, or that

member of the locking means which is carried by the front wall of the base, thus performing the additional function of the means of attachment of the chain, while the seat in receiving the chain when the foot-rest is within the receptacle permits the cover of the receptacle to be closed down tightly upon the upper edge of the front wall.

Having thus described the invention, what is claimed is—

In a shoe-polishing stand, a hollow base having spaced seats opening upwardly in its front wall and with a stationary top portion at the rear, a front portion hinged to said stationary top portion and bearing over said

seats and closing the open ends of the same, a stop member within said base and bearing on the bottom thereof and provided with recesses in the lower edge in alinement with said seats, and bars extending through said seats and engaging said recesses at their inner ends and with foot-rests at their outer ends.

In testimony that I claim the foregoing as my own I have hereto affixed my signature in the presence of two witnesses.

PETER HENRY HIXON.
